FLUSHING APPARATUS

Per Gustaf Hörnell, Lidingo, Sweden

Application August 23, 1933, Serial No. 686,453
In Germany August 26, 1933

10 Claims. (Cl. 4-7)

Contrivances for the flushing of the external surfaces of the cavities of the human abdomen are previously known, the flushing liquid being ejected or sprayed in the form of a jet or jets 5 within a jacket open at both ends, from one or more nozzles located adjacent to or in the jacket wall, the direction of the jet or jets forming an angle with the geometric axis of the jacket. The spray device may be formed by one or more openings 10 provided in the wall of the jacket, said openings being directed obliquely upwards. The spray liquid then hits the parts of the body to be flushed, either directly or indirectly by being ejected against the jacket wall opposite to the inlet openings, whence the liquid is sprayed in a broken or dispersed state against the part of the body in question.

It has been found that this construction suffers from certain deficiencies both in regard to 20 the manufacture and with respect to the use of the flushing apparatus. On the one hand, the douche, when hitting the surface of the body directly should have a comparatively great width and, on the other hand, that portion of the jacket 25 which is brought into contact with the stream of spray liquid, such as a stream of water, issuing from a supply body should be kept as small as possible. For these reasons it has been found unsuitable to give all of the passages extending 30 through the wall of the jacket the same direction. If the longitudinal axes of the passages be directed conically, for instance, relatively to each other, the manufacture of the device will be rendered difficult and expensive. If, on the other 35 hand, the spreading of the douche were to take place by the jet or jets hitting a part of the jacket wall and by said jet or jets being deflected back against the surface of the body in question, the flushing power of the water would be considerably reduced.

In addition, the provision of a water-tight connection between the perforated jacket wall and the exit of the liquid-supplying device would, in the presence of a great water pressure on the 45 outside of the jacket wall, for instance as described in my co-pending application Serial No. 510,523, now Patent No. 1,983,329, give rise to constructional difficulties, while involving also the disadvantage of a considerable portion of the 50 external surface of the jacket being wetted.

The present invention refers to an improved construction, whereby said inconveniences are obviated. The principal feature of the invention is a device for the flushing of the cavities of the 55 human abdomen, said device consisting of a

jacket open at the top and the bottom and provided with a spray device and with a handle, the spray being ejected laterally of the geometrical axis of the jacket, and the invention is substantially characterized by one or more openings in a supply body for flushing liquid, said openings being arranged outside and/or below the wall of the jacket, the flushing liquid being forced out through said openings and ejected into the space enclosed by the jacket by reason of the kinetic energy already imparted to the liquid outside and/or below the jacket. The wall of the jacket may have one or more passages or slits extending therethrough, the liquid issuing from the opening or openings of the supply body for the flushing liquid being introduced through said passage or passages, the opening or openings of the passage or passages on the outside of the jacket being preferably located either adjacent to the exit opening or openings of the supply body for the flushing liquid or at some distance from said exit opening or openings, while the liquid outlet or outlets of the supply body for the flushing liquid may also be arranged in such a manner that one or more atomized jets may bypass the 25 jacket wall and be sprayed into the interior of the jacket, for instance from a point below the lower border of the jacket.

Other features characteristic of the invention will be set forth in the following description of 30 a few embodiments thereof, reference being had to the accompanying drawing in which,

Fig. 1 is an elevation of one embodiment of the invention;

Fig. 2 represents a corresponding partial section;

Fig. 3 is a cross-section on line III-III in Fig. 2;

Fig. 4 shows a plan view of that portion of the jacket with which it is placed against the outlet 40 of the supply body for the liquid illustrated in Fig. 2;

Fig. 5 shows the jacket viewed from below;

Fig. 6 is a plan view of the outlet end of the supply body to which the jacket is connected;

Fig. 7 shows a part broken off the outlet end illustrated in Fig. 6;

Fig. 8 shows diagrammatically a vertical longitudinal section of a further embodiment;

Fig. 9 also is a diagrammatic representation of 50 a further embodiment shown in vertical longitudinal section.

In the drawing, 1 designates a hollow cylindrical jacket pipe which is movably arranged on the cylindrical part 2 which serves as a valve hous- 55

ing. The jacket pipe is provided with a bore, through which the bent-down end portion 3b of the L-shaped part 3 is extended. The one shank of this part 3 is provided with a handle 4. The bent-down end portion 3b is fitted into a recess 3c in the part 2. As illustrated in Fig. 2, the front surface of the bent-down end portion 3b is shaped so as to engage a correspondingly shaped surface of said recess. Provided on the end of the part 3b is a projection 5 bearing against a correspondingly shaped surface of the recess. A closure device consisting of a stopper 6 is screwed into the rear end of the part 2. Inserted between the projection 5 and the inner circular surface of the stopper 6 is a spring 7. A disk 8 of brass, for instance, and provided with a central aperture bears on a shoulder inside the jacket pipe 1. This disk is influenced by a pressure spring 9 which is compressed between the disk 8 and an annular flange 10 of the part 6, said spring thus exerting a pressure on the disk and consequently on the jacket pipe 1, so that the latter will be pressed to the left in the embodiment shown in Fig. 2, the several parts taking the position illustrated in this figure when the device is not operated. Provided in the left half of the part 2 is a longitudinal bore 11 receiving a valve spindle 12 carrying a circular valve disk 13. When the device is not operated, said disk 13 bears on a packing 14 provided between the part 2 and a cylindrical part 15 screwed into the part 2 (see Fig. 2), and the water supply is cut off from the bores 16 provided in the left hand wall (Fig. 2) of the jacket pipe 1, a spring 17 surrounding the spindle 12 pressing the disk 13 against the packing 14, so that the central opening in the latter will be closed. The liquid pressure prevailing within the part 2 as well as the pressure of the springs 9 and 17 aid toward keeping the valve disk in closed position. 18 denotes a packing, consisting of rubber, for example. The left end (compare Figs. 2 and 3) of the jacket pipe 1 is provided with an undercut recess 20 (Figs. 6 and 7), the edges of the recess converging downwardly, as illustrated in plan view in Fig. 6. The outlet openings 16 (Fig. 6) open into this recess 20. Removably connected to this end is the jacket 19 surrounding the sprayed-out liquid, a dove-tailed projection 21 on the right hand wall of the jacket (Fig. 2) being introduced into the undercut recess 20. The projection 21 has two passages of a suitable cross-sectional area extending therethrough, the liquid forced out from the openings 16 being introduced through said passages into the space within the jacket.

Through an inlet opening 23, to which the one end of a flexible reinforced tube may be connected in any suitable manner, the interior of the body containing the valve is in connection with a water-supplying means such as the ordinary domestic water-supply system.

In operation, the device is grasped by the hand, the upper edge of the jacket 19 being laid against the part of the body to be flushed.

As will be seen from Figs. 1, 2 and 3, a relative movement between the handle 4 and the right-hand part 4a of the liquid-supplying body is sufficient to bring about a displacement of the jacket pipe 1 to the right (Fig. 2), this movement being effected most conveniently by the handle 4 being grasped with the ball of the hand and the part 4a with the index-finger, the two parts being thus approached to one another.

When the jacket pipe 1 with the jacket 19 positively secured thereto is displaced to the

right (Fig. 2), the valve spindle 12 will also be pressed to the right by a projection 23a on the perforated head wall of the jacket pipe 1, against the liquid pressure and the influence of the springs 9 and 17, the valve disk 13 being then lifted from its seat and a connection established between the interior of the device (bore 11) and the openings 16. Through the latter, flushing liquid is then ejected, which liquid is forced through the passages 22 of the jacket wall by reason of the kinetic energy imparted to the liquid already outside the jacket. As illustrated in Fig. 2, the liquid jets ejected through the openings 16 will hit baffle surfaces provided in the passages 22. Through the baffle effect the jet of liquid will be dispersed in the form of a douche directed obliquely upwards against the area limited by the upper edge of the jacket 19. The passages 22 have such a cross-sectional area, or are otherwise formed in such a manner, that a considerable spreading of the flushing liquid is obtained within the jacket.

If upon completed flushing the pressure by means of which the parts 4 and 4a were moved towards each other be discontinued, the parts 25 will return into their original position shown in Fig. 2 through the influence of the springs 9 and 17, aided by the water pressure in bore 11, the valve disk being then again brought back onto its seat so as to cut off the connection between the interior of the liquid-supplying body and the apertures 16. Finally the spring 9 causes the handle 4 to remain fixed with respect to the other parts of the device. It is obvious that the lever action produced by the handle 4 and the parts adjacent thereto may be produced by any system having a handle, the jacket pipe 1, the part 2 and pivots provided at a suitable point. It is also evident that the water supply within the jacket wall may also be effected by the jacket being forcibly pressed by means of handle 4 against a part of the body located in the proximity of the part to be cleaned, and that the handle will then approach the part 4a, as indicated by the arrow in Fig. 1. In this case 45 part 4a need not be operated.

When the parts of the device return into their initial position, the perforated head of the jacket pipe 1 is removed from the end of the cylindrical body 15 facing the same. Hereby to a certain extent a vacuum is set up within the part 2. In order to prevent any used flushing liquid that may still be present in the passages 22 from being again sucked into the bore 11 through the openings 16 due to the action of this vacuum—which would give rise to the obvious inconvenience that in a subsequent flushing such sucked-in liquid would contaminate the fresh quantities of water—there are provided in the joint between the liquid-supplying body and the jacket wall 60 facing the same, air passages, such as slit-like recesses 24, in the jacket projection 21, such air-passages communicating with the outlet for the flushing liquid. On any pressure below atmospheric ensuing within the liquid-supplying body 65 air will be sucked in through these air passages and through the openings 16, forestalling thereby a non-desirable vacuum. Thus a small distance will be produced by the recesses 24 between the openings 16 and the passages 22. Provided the 70 openings and passages in question are suitably formed with regard to their shape and size, the whole quantity of liquid ejected from the openings 16 will be introduced through the passages 22, and further no flow of the used flushing water 75

toward the outside of the jacket will take place. As no water pressure, but rather a reduction of the air pressure is produced in the joint 20-24 (by injector action), no packing means are required between the removable jacket and the liquid-supplying device.

Fig. 8 shows diagrammatically a vertical longitudinal section of the outlet end together with the jacket of a further embodiment of the device according to the invention. Here, 25 designates the inner space (corresponding to the bore 11 in Fig. 2) of the hollow body, into which water enters under pressure on the operation of any suitable device, not shown. 26 is a jacket removably secured to the part 25 by means not shown. 27 denotes an outlet opening located outside and below the outer jacket wall. When the flushing water is admitted, this water enters into the space 25 under pressure and is forced out through the opening 27 as a powerful jet. Opposing the opening 27 is a baffle surface 28, transforming the jet into a douche directed obliquely upwards against the area limited by the upper border of the jacket. The baffle surface 28 is formed so as to impart to the douche a sufficient width. It will also be possible by a suitable construction and disposition of the baffle surface to influence the other properties of the douche. It is by no means necessary that the opening 27 be disposed at a distance below the lower border of the jacket. The opening may be arranged in close proximity to the border of the jacket, or somewhat higher, in which latter case the jacket wall will at a corresponding point be provided with a bore or an opening, or with a slit extending by a certain distance upwardly from the lower border of the jacket. This obviously will be true also with respect to the embodiment shown in Figs. 1-7.

Evidently, the opening 27 may be formed in such a manner that the water jet is caused to impinge upon the opposite portion of the inner wall of the jacket so as to be dispersed into a douche without the aid of a special disk 28. The flushing power, however, will be reduced hereby, and this arrangement can be recommended only where a great water pressure is available.

According to experience, there is, with the embodiment shown in Fig. 8, the possibility, even if it is small, that used flushing water drops off the jacket onto the disk 28 when the flushing operation has been completed, or, if no disk is present, may come into contact with the wall of the opening 27. As from a hygienic point of view it is desirable that each jacket be used by one individual only, and that the flushing water already used should come into contact neither with another jacket nor with other parts of the device, preference should be given in said respects to the embodiment described with reference to Figs. 1 to 7.

Fig. 9 shows diagrammatically a further embodiment of the outlet end together with the jacket of a device according to the invention. Here, 25' designates the inner space (corresponding to the bore 11 in Fig. 2) of a hollow body into which water is admitted under pressure on the operation of a regulating device, not shown. 26' is a jacket removably secured to the part 25' by means not shown. 27' denotes an outlet opening situated outside the jacket and at the upper border of the same. When the said device for the flushing water is operated, the latter enters into the space 25' under pressure and is forced out through the opening 27' as a powerful jet.

Opposing the opening 27' there is a baffle surface 28' for the purpose set forth with reference to Fig. 8.

The principle of the invention may be expressed thus that one or more coherent jets of flushing water entirely surrounded by a wall and limited by walls on all sides are released for good or temporarily already outside the jacket wall or above or below the border of this wall, or outside and/or above or below this border.

In place of the two openings 16, Fig. 2, there may be a greater number of openings or a single opening, provided that the number of passages 22 is correspondingly increased or decreased, or that other alterations are made with regard to these passages, corresponding to the position and the number of the outlet openings 16.

In connection with the device shown in Figs. 1-7, the transformation of the liquid jets into a douche takes place by the jets impinging upon the bottom surfaces of the passages 22 provided in the wall of the jacket. This transformation may also take place in some other manner, for instance by the insertion of suitable baffle disks or plates between the openings 16 and the passages 22. Also, the opening or openings 16 as well as the passage or passages 22 may be provided with baffle surfaces, or be caused to cooperate with baffle surfaces, in order to effect the dispersion of the liquid in stages. It is also possible to give the openings 16 such a shape, or to make these openings cooperate with such baffle surfaces, outside the jacket, that the flushing liquid issuing therefrom would take the form of a douche without being subjected to any further influences. Furthermore, the douche could be produced outside the jacket wall by the arrangement of a plurality of smaller outlet openings in the supply body, either a plurality of passages or a single passage or slit of a greater cross-sectional area being then provided in the wall of the jacket.

Finally, there is the possibility, as hereinbefore stated, to cause the flushing liquid to bypass the jacket wall, for instance at a point below the jacket border, and to be sprayed into the interior of the jacket in the form of a jet or jets that may be dispersed, if desired, such dispersion then being effected in any suitable manner, for instance by baffle plates and/or a suitable construction of the spray nozzle or nozzles.

In such embodiments where the liquid is introduced into the interior of the jacket through one or more passages extending through the jacket, it may be preferable to have the cross-sectional area of the passage or passages increasing in a direction toward the inner wall of the jacket, if desired over a restriction. It is also possible to form the opening or openings (compare 16, Fig. 2) of the liquid-supplying body in such a manner that they are flared outwardly, so as to transform the ejected liquid into a douche which is forced into the interior of the jacket below the lower border thereof or through one or more openings or slits provided in the jacket wall. When there are a plurality of openings (16) in the supply body, the size, number and direction of these openings may be chosen so that the liquid leaves the supply body as a douche which is then introduced, into the space limited by the jacket, below the lower border of the jacket or through one or more openings or slits provided in the jacket wall. Any combinations of the embodiments described obviously fall within the scope of the invention.

What I claim is:—

1. In a device for the flushing of the external

surfaces of the cavities of the human abdomen, the combination with a jacket open at the top and bottom, of a spray device for directing a free jet of flushing liquid into and laterally of the 5 geometrical axis of the jacket, said spray device comprising a supply body for a flushing liquid, and jet-projecting apertures extending through the wall of said supply body, said apertures being located in a portion of the wall of said body exterior to and positioned laterally of said jacket 10 and being directed into and laterally of the space enclosed by said jacket; whereby the jet of flushing liquid ejected into said jacket is, after disintegration into a spray, directed against the area bounded by the upper border of said jacket.

15 2. A device as claimed in claim 1, wherein the said apertures of the supply body are positioned to eject flushing liquid in jet form below the wall of said jacket.

20 3. A device as claimed in claim 1, wherein the said apertures of the supply body are positioned to eject flushing liquid in jet form above the wall of said jacket.

25 4. A device as claimed in claim 1, wherein the wall of said jacket is provided with openings, and the said apertures of the supply body are positioned to direct a jet of flushing liquid through 30 said openings.

30 5. A device as claimed in claim 1, wherein the wall of said jacket is provided with openings, and the said apertures of the supply body are positioned adjacent to but spaced from said openings in the jacket wall.

35 6. A device as claimed in claim 1, wherein the wall of said jacket is provided with openings through which the liquid ejected through the

apertures of the supply body enters the jacket, in combination with means associated with said openings for dispersing into spray form the jet of liquid projected from said apertures.

7. A device as claimed in claim 1, wherein the wall of said jacket is provided with openings through which the liquid ejected through the apertures of the supply body enters the jacket, in combination with baffle surfaces at said openings for dispersing into spray form the jet of 10 liquid projected from said apertures.

8. A device as claimed in claim 1, wherein the wall of said jacket is provided with openings through which the flushing liquid enters said jacket, said openings increasing in cross-sectional 15 area in the direction towards the inner surface of the jacket wall.

9. A device according to claim 1, characterized in that the supply body and jacket are in contact and an air passage communicates with the 20 aperture of the body to prevent induction of used liquid from the jacket and into the supply body by reason of occurrence of pressure below atmospheric within the supply body upon termination of the flushing operation.

25 10. In a device for flushing the external surfaces of the cavities of the human abdomen, the combination with a jacket comprising a wall open at the top and bottom, of means for directing a spray of flushing liquid upon the area defined 30 by the upper rim of said jacket; said means comprising nozzle means at the exterior of and spaced from the said jacket wall for directing a jet of flushing liquid into the said jacket and at an angle to the axis thereof.

35 PER GUSTAF HÖRNELL.
